(57) **CLAIM**

The ornamental design for a recreational flotation device, as shown and described.

DESCRIPTION

FIG. 1 is a perspective view of a recreational flotation device in accordance with my new design.

FIG. 2 is an elevation view of the recreational flotation device as seen from the left side of FIG. 1, the opposite side view being a mirror-image.

FIG. 3 is a top plan view

FIG. 4 is an elevational view as seen from the curved front end of the recreational flotation device of FIG. 1.

FIG. 5 is an elevational view as seen from the rear of the recreational flotation device of FIG. 1; and,

FIG. 6 is a bottom plan view.

The broken lines shown in the drawing are for illustrative purposes only and form no part of the claimed design.
